UNITED STATES PATENT OFFICE

JOHN L. SAGER, OF LOS ANGELES, CALIFORNIA

WELL DRILLING STRUCTURE

Application filed August 16, 1929. Serial No. 386,468.

My invention relates to electro-magnetic reciprocating means, and more particularly to a novel solenoid-operated well drilling apparatus.

5 Present well drilling methods require such bulky and expensive equipment as to make the drilling of a well an expensive matter, usually requiring expert help.

It is an object of the present invention 10 to provide a well drilling apparatus which is substantially automatic when in operation, and which is yet simple in design and comparatively cheap.

15 A further object of the invention is to provide a reciprocating drilling mechanism which may be suspended in a well on any suitable supporting means and which is automatically advanced downward at the proper time to insure a maximum percussion.

20 In accomplishing the above and other objects I provide a plurality of solenoids each of which acts on a plunger, at least certain of these solenoids being operable to exert a downward force on the plunger, and certain 25 others being adapted to exert an upward force on the plunger, and it is one of the important objects of this invention to provide a plurality of solenoids so arranged, these solenoids being hereinafter termed advancing and retracting solenoids for the purpose 30 of clearness.

I have found that with such a combination it is preferable to energize the advancing solenoids during the period of energization of the 35 retracting solenoids, and to then rapidly break the circuit through the retracting solenoids, thus allowing the advancing solenoids to quickly accelerate the plunger on the power or percussion stroke. I have found 40 that the acceleration of the plunger is very much faster if this procedure is followed than it would be if the retracting and advancing solenoids are successively energized. This is due to the fact that the current through a 45 highly inductive winding builds up very slowly, a major portion of a second often elapsing before this current reaches a maximum. The magnetic flux is correspondingly slow to build up, and it has thus previously 50 been impractical to use the action of such

solenoids in lowering a plunger of this type.

It is thus a very important object of this invention to provide advancing and retracting solenoids acting on a plunger in opposite directions, these solenoids being simultaneously energized during a portion of the cycle, this portion being preferably just prior to the de-energization of the retracting solenoid when used in the percussion method of drilling.

Another object of the invention is to provide a manipulative method of thus operating a drilling structure or other reciprocating structure provided with both advancing and retracting solenoids.

A further object of the invention is to provide a drilling or reciprocating structure built in units, each unit including a solenoid, so that any number of these units may be assembled, depending upon the strata being penetrated as well as upon other factors, and so that any defective unit may be easily removed and replaced.

Further objects of the invention lie in the construction of these solenoid units, per se.

Still another object of the invention lies in combining a water-circulating system with a solenoid-operated reciprocating mechanism whereby the solenoids are water cooled, thus permitting the permissible safe current in the windings to be greatly increased.

Another object of the invention lies in the provision of a cushion means for preventing the plunger from dropping from the drilling structure.

Still further objects and advantages of this invention will be evident hereinafter.

While I shall hereinafter describe in detail that embodiment of my invention which I deem best for drilling purposes it should be understood that I am not limited to this embodiment, certain of the details of my invention finding utility in other capacities.

Referring to the drawings:

Fig. 1 is a utility view illustrating my drilling apparatus in a well.

Fig. 2 is a vertical sectional view of the drilling structure of my invention.

Fig. 3 is an enlarged view of a portion of Fig. 2.

Figs. 4, 5, 6, and 7 are sectional views taken along corresponding lines of Fig. 2.

Fig. 8 is an enlarged view of another portion of Fig. 2.

5 Fig. 9 is a general wiring diagram of the apparatus of my invention with certain of the parts shown in perspective.

10 Fig. 10 is a wiring diagram of an alternative form of advancing means of my invention.

15 Referring in detail to Fig. 1, I have shown a well 10 being drilled by a drilling structure 11 of my invention, this structure being suspended in the well by means of a supporting means illustrated in the form of a wire cable 12 which extends over a sheave 13 rotatably supported in a tripod or derrick 14. The end of this wire cable is wound around a lowering means in the form of a drum 15 so that 20 by rotating this drum the drilling structure 11 may be raised or lowered in the well.

25 The drilling structure 11 is formed of any number of solenoid units 16 separated by spacing structures 17. In Fig. 2 I have shown a cross section of such a drilling structure as providing two solenoid units 16 and two spacing structures 17, and being adapted to reciprocate a plunger 18 whereby the well 10 is deepened through the action of a bit 19 30 attached to the lower end of this plunger.

35 The upper of these solenoid units has been termed a retracting unit 20 while the lower one has been termed an advancing unit 21, this nomenclature being used because of the respective functions of these units in retracting and advancing the plunger 18. Inasmuch as the solenoid units are substantially identical, as are also the spacing structures 17, only the uppermost solenoid unit and spacing 40 structure will be specifically described.

45 Referring in particular to Figs. 2, 3, 5, 6 and 7, the novel solenoid unit of my invention is housed in a shell 22 formed of magnetic material and having primary and secondary counterbores 23 and 24 which are threaded to respectively receive primary and secondary plugs 25 and 26 which are in turn adapted to bear against primary and secondary plates 27 and 28 in a manner to force 50 these plates into firm engagement with the shoulders defining the ends of the counterbores 23 and 24 in which they are respectively positioned.

55 Formed respectively in the plugs 25 and 26 are packing chambers 31 and 32 into which are threaded primary and secondary retaining members 33 and 34, each of these members having an annular channel 35 adapted to snugly engage the periphery of an inner tubing 36 formed of a suitable non-magnetic material. The retaining members 33 and 34 are adapted to be screwed into their respective packing chambers by means of a suitable wrench extending into openings 36a thereof, 60 these members engaging the opposite ends of

the inner tubing 36 in abutting relationship.

65 A suitable packing 37b is retained in each of the packing chambers 31 and 32 and is adapted to be compressed by the retaining members 33 and 34 against the walls of these 70 packing chambers and again the periphery of the inner tubing 36 when the retaining members are in abutting relationship relative to the ends of the inner tubing 36, thereby forming a fluid-tight joint between the inner 75 tubing 36 and its associated plugs and retaining members. The solenoid unit 16 is so designed that when the retaining members are in this position, and when the plugs 25 and 26 are in engagement with the plates 27 80 and 28, the faces of the plugs and retaining members are flush with the respective ends of the shell 22.

85 Pressed tightly into a central opening of each retaining member is a suitable sleeve adapted to loosely journal the plunger 18 in its reciprocatory motion, these sleeves being respectively designated as primary and secondary sleeves 37 and 38. The primary sleeve 37 is usually, though not invariably, 90 formed of magnetic material, while the secondary sleeve 38 is formed of non-magnetic material, the utility of thus forming the sleeves being evident hereinafter. The primary and secondary plugs 25 and 26 thus 95 respectively cooperate with the retaining members 33 and 34 and their associated sleeves 37 and 38 in defining primary and secondary closure means extending between the shell 22 and the inner tubing 36. 100

105 Positioned in a chamber formed between the tubing 36 and the shell 22 and between the plates 27 and 28 is a retracting solenoid winding 40 preferably formed of a plurality of groups 40a wired in parallel. This retracting solenoid winding is annular in shape and the inner diameter thereof is slightly greater than the external diameter of the inner tubing 36 so as to provide an annular wiring space 41 therebetween in which space are positioned the wires connecting the groups of the winding 40, these wires extending through notches 42 cut in the plates 27 and 28 and into primary and secondary pull boxes 43 and 44 formed by cavities respectively cut in the plugs 25 and 26 adjacent the plates 27 and 28. A passage 45 communicates with the pull box 43 and extends upward through the primary plug 25, there being a similar passage 46 formed through the secondary plug 26. 110 115

120 Each spacing structure 17 is provided with upper and lower flanges 47 and 48 through which cap screws 49 extend in a manner to be threadedly received by the plug there-adjacent. A spacing structure 17 is thus clamped to each end of the solenoid unit 16. A plurality of ribs 50 extend longitudinally of each spacing structure between the flanges 47 and 48, one of these ribs being cored to 125 form a passage 51 in alignment with the pas- 130

sages 45 or 46 and adapted to retain the conductors supplying current to the solenoid units 16, as well as any control conductors.

These conductors extend upward through 5 a passage 52 formed longitudinally through a rib 53 of a strainer 54 formed with a pair of flanges 55 and 56 which are respectively bolted or otherwise secured to a flange 57 of a cap member 58. This cap member provides a 10 wire chamber 59 which communicates with the upper end of the passage 51 through a radial passage best shown in Fig. 2.

The conductors leave the cap member through a suitable packer 60 preferably in the 15 form of an insulator, and extend upward around a hook 61 to the main wire cable 12, the hook 61 being attached to the lower end of this cable and serving to support the drilling structure 11 through an eye 62 formed 20 integral with the cap member 58. The wire cable 12 is shown in cross section in Fig. 4 and is composed of stranded sections 63 formed of a material of high tensile strength and surrounding power conductors 64 in protecting relationship, these power conductors carrying current to the drilling structure and also providing any control wires desirable 25 in operating this structure.

The advancing unit 21 houses an advancing 30 solenoid winding 68 in a manner previously described for the retracting unit 20. The construction of these two units is substantially identical except that the plug fitting in the lower end of the shell 22 provides a channel 74 corresponding to, and serving the same purpose as, the channels provided in the retaining members 33 and 34 and into which the inner tubing 36 extends. A packing chamber 75 is formed in this plug and a gland 40 76 compresses a packing 77 therein and pressurally against the peripheral surface of the plunger 18.

The plunger 18 is composed of alternate sections formed of magnetic and non-magnetic material which are of the same external 45 diameter and preferably threaded together as shown, the former acting as armatures for the solenoid units and the latter acting as spacers therefor. For the purpose of clearness I have termed the upper section formed of magnetic material as a retracting armature 50 78, and the lower section of this material as an advancing armature 79, the section of non-magnetic material therebetween being designated as an intermediate spacer 80. Similarly the section of non-magnetic material below the advancing armature 79 has been 55 termed a bit-retaining member 81 due to the fact that the bit 19 is attached thereto.

60 The magnetic path through the retracting unit 20 includes the shell 22, the plugs 25 and 26, and the retaining members 33 and 34—all formed of magnetic material—and also includes the sleeve members 37 and 38, and that 65 portion of the retracting armature 78 lying

between the retaining members. If this armature is centrally disposed relative to the remainder of the magnetic circuit the length thereof is sufficient to bridge the sleeve members 37 and 38 so that the reluctance of the magnetic path will be a minimum, the position of maximum upward thrust being just before this armature bridges the sleeve members. In some instances I have found it desirable to form 70 the primary sleeve member 37 of magnetic material and the secondary sleeve member 38 of non-magnetic material so that the action between the former sleeve member and the retracting armature 78 when the retracting 75 solenoid is energized is one of two magnets in physical contact with each other. This contact magnetic action strongly tends to maintain the plunger in its upper or retracted position during the energization of the advancing solenoid, but this force is quickly removed when the solenoid is de-energized. If this action is not desired it is essential that both the sleeve members 37 and 38 be formed 80 of non-magnetic material to prevent magnetic binding of the plunger thereto when the solenoid winding is energized and when quick action of the plunger is desired. 85

Similarly it is sometimes preferable to form the upper sleeve member of the advancing unit 21 of non-magnetic material and to form the lower plug and gland 76 of magnetic material, thus tending to exert a very powerful downward thrust on the advancing armature 79 just prior to the instant that this 90 armature moves downward into contact with the magnetic material forming the plug. This position of maximum downward thrust which is reached just prior to contact between the advancing armature 79 and the 95 plug is a very important one in the drilling art as will be hereinafter explained. 100

It will be noted from Fig. 2 that the intermediate spacer 80 is of such length that the center-to-center distance between the armatures 78 and 79 is different from the center-to-center distance between the retracting and advancing units 20 and 21, this distance in the preferred embodiment of my invention being less than the latter distance. Thus by 110 alternately energizing the retracting and advancing solenoid windings 40 and 68 the plunger 18 will be reciprocated. 115

I have found, however, that such an alternate energization does not give the desirable blow obtainable if the retracting solenoid is first energized followed by a similar energization of the advancing solenoid and a subsequent de-energization of the retracting solenoids. This desirable cycle I accomplish 120 by means of a timing device best illustrated in Fig. 9 which illustrates advancing and retracting relay contacts 90 and 91 formed of spring steel and tending to respectively engage contacts 92 and 93 when not lifted there- 125 130

from by cams 94 and 95. These cams are mounted on a single shaft 96 which is driven by a small variable-speed motor 97 through a suitable speed-reduction means 98. The relay contacts 90 and 91 are respectively connected to solenoids 100 and 101 by conductors 102 and 103, the remaining terminals of these solenoids being connected together by a conductor 104 which also extends to a source of electric energy indicated as a generator 105, this generator being connected to the contacts 92 and 93 by means of a conductor 106.

The solenoids 100 and 101 respectively act when energized to pivot armatures 108 and 109 around a pivot shaft 110 against the action of springs 111 and 112 in a manner to close the main contacts supplying current to the solenoids of the drilling structure. These main contacts comprise a pair of contacts numbered respectively 113 and 114 which are connected to the generator 105 by a conductor 115 and which lie in the path of travel of spring contacts 117 and 118 mounted on the armatures 108 and 109.

The contacts 117 and 118 are preferably formed so as to be quickly and easily replaced, this being accomplished by means of thumb screws 119 threaded into the armatures and bearing against these contacts. Conductors 120 and 121 respectively connect the contacts 117 and 118 to slip rings 122 and 123 mounted on one end of the drum 15, these slip rings being respectively connected to the advancing and retracting solenoids of the drilling structure through the conductors 64 of the cable 12. Current returns from both the advancing and retracting solenoids through a common return conductor 125 which ends in a slip ring 126 from which the current is conducted to the generator 105 through a suitable brush and through a conductor 127.

Due to the high inductance of the retracting and advancing solenoid windings it often is necessary to use quick-acting circuit breakers and auxiliary means for quenching the arc formed when the circuits are opened. This is especially true of the circuit including the retracting solenoid, for the strength of the blow delivered is materially decreased by any current passing through the arc formed between the contacts 114 and 115 when separated during the period of energization of the advancing solenoid. For this reason I have shown a magnetic blow-out means for these contacts, this means comprising a magnetic core 130 bridging the gap formed by the contacts 114 and 118 when separating, the magnetic flux being formed by a winding 131 around one leg of the core 130, this winding being connected across the generator 105 through a switch 134. It is usually preferable to use a similar blow-out means for the contacts 113 and 117 to prevent undue pitting of these contacts due to arcing conditions.

The currents required in operating the solenoids is sometimes large enough to require an external cooling means for these solenoids. Such a means is incorporated as an integral part of my drilling structure and utilizes a longitudinal bore 149 of the spacing structure 17 above the retracting unit 20 as a cylinder in which a piston 150, formed integral with the uppermost non-magnetic section 151, may reciprocate when the plunger moves. This piston carries the customary working valve 152 which controls the passage of fluid through a longitudinal passage 155 formed completely through the plunger 78 and which communicates with a passage in the bit 19 which directs the discharge of this fluid adjacent a cutting edge of the bit, thus aiding in drilling and in keeping the bit clean.

This fluid is drawn through relatively large openings formed through the walls of the strainer 50 and passes through a standing valve 159 screwed or otherwise secured in the longitudinal bore 149. The standing valve and the openings of the strainer 50 are so formed as to have relatively large fluid-carrying capacities so that the pumping means will not materially slow up the downward or power stroke of the mechanism. The space below the piston 150 may freely receive and discharge air or liquid through the sleeves 37 and 38 and around the periphery of the plunger. In order that no retarding effect may be thus set up, the journalling openings of the sleeves may have longitudinal channels 161 cut therein as best shown in Fig. 7.

The piston 150 prevents the plunger 18 from dropping from the drilling structure, but the weight of the plunger is ordinarily large and to prevent possible damage should the current be cut off when the drilling structure is a distance from the bottom of the well, or should the bit 19 penetrate an excessively soft formation, I prefer to provide a cushion means acting between the piston 150 and the top of the retracting unit 20.

This cushion means may be any suitable hydraulic one or may be of the type illustrated in which compression springs 162 rest on the upper face of the primary plug 33 115 and lie in the path of travel of the piston 150 when moving into its lowermost position, it being understood that the springs come into play only after the solenoid has passed the position of maximum thrust when moving downward.

If maximum drilling efficiency is to be achieved it is very desirable for the operator to know the position of the plunger relative to the drilling structure at or toward the end of each stroke. The desirability of this will be apparent when considering the characteristics of such a drilling structure as described wherein the maximum downward thrust on the plunger occurs just before the advancing armature 79 bridges the magnetic 130

gap of the advancing unit 21 and wherein this portion of the stroke is used in actual drilling to secure maximum percussion. It is usually desirable that the instant of impact be at or just before this position of maximum downward thrust. If the drilling structure is positioned a trifle too deep in the well, this position of maximum downward thrust is never reached and the full efficiency of the structure is not utilized.

For the purpose of indicating to the operator whether or not this position of maximum downward thrust is reached on each reciprocation I provide a roller 200, best shown in Fig. 8, which is rotatably mounted in a support 201 which in turn is secured to a flexible diaphragm 202 flexed in such a manner as to cause the roller to pressurally engage the periphery of the plunger 18 at all times. An annular groove 204 is formed in the intermediate spacer 80 in such a position that the roller moves thereinto when the plunger is at a "control" position, which position is just prior to the relative positions of advancing armature and advancing solenoid for maximum downward thrust.

A switch contact 205 is mounted on the opposite side of the diaphragm 202 from the roller 200 and engages a spring contact 207, suitably mounted in a switch cavity 208 of the spacing structure, when the roller enters the annular groove. The engagement of these contacts completes a control circuit which includes a conductor 210, the common conductor 125, a slip ring 212 carried by the drum 15, a conductor 213 extending to the generator 105, and an indicating means in the form of a signal lamp 215. Thus, when the signal lamp 215 is lighted the operator knows that the drilling structure may be further lowered and that the plunger is moving through the position of maximum thrust.

It is often desirable to make this advancement of the drilling structure automatic, and in accomplishing this end some means is needed for controlling the lowering of the drilling structure as a function of the energization of the control circuit. Such a means is shown in Fig. 9 as comprising a solenoid-operated brake 225 for controlling the rotation of the drum 15 under the action of the weight of the drilling structure. Diagrammatically I have shown this brake as being released by the lowering of the free end of a lever 226 which is resiliently forced upward by a spring 227 but which is drawn downward by the action of a solenoid 228, the winding of which is energized from a battery 229, or other source of electric potential, in circuit with a time-limit relay 230, the time setting of which may be readily changed by moving a thumb screw 231. The control winding 232 of this time-limit relay may be connected in parallel with the signal lamp 215 so as to be energized each time the

signal lamp is energized. The setting of the time-limit relay thus varies the time of energization of the solenoid 228 and thus the time that the brake 225 is released.

In Fig. 10 I have illustrated an alternative automatic advancing means which includes a positive drive means for advancing the drilling structure. This is accomplished by a motor 241 connected to the drum 15 by a link belt 242 or other speed-reduction means. A quick-operating magnetic brake is used on the motor shaft, the winding of which is indicated by the numeral 243. This type of magnetic brake is held in locked position by spring-operated means and is released only during the energization of the winding 242. Inasmuch as this winding is connected directly across the supply terminals of the motor, it follows that such a magnetic brake insures quick stopping of the motor the instant the power supply thereof is shut off. This supply of power is controlled by a suitable time-limit relay 245 of any suitable design, such, for instance, as one having a dash-pot for retarding the opening of the power circuit once the control circuit has been energized. This control circuit is connected across the terminals of the lamp 205 as previously suggested.

In assembling the drilling structure it is preferable to wire the groups 40a of each solenoid unit in parallel, using a pair of flexible supply conductors for this purpose which extend through the wiring space 41, the pull boxes 43 and 44, and through the passages 45 and 46, these conductors extending slightly beyond the latter passages to permit splicing to a similar pair of conductors extending through the passage 51 of the spacing structure 17 which is to be subsequently secured thereadjacent. After this splice has been made the bolts 49 are secured in place, the excess wire being forced into the pull box thereadjacent. Any number of solenoid units may be thus assembled, it being understood that the supply conductors of the advancing units extend through the passages of the retracting units, as does also the control wire 210 from the roller-operated switch.

The desired number of magnetic and non-magnetic sections are then assembled to form the plunger 18 which is put in place before the spacing structure is secured to the uppermost unit 20. The supply and control conductors are then spliced to the conductors 64 of the wire cable 12 and the excess wire forced into the chamber 59 of the cap member 58.

The drilling structure is then lowered into the well and the motor 97 energized. As the cam 95 moves, the spring contact 91 lowers thus completing a circuit from the generator through the conductors 103, 104 and 106 in a manner to energize the solenoid 101 which attracts the armature 109 against the action of the spring 112 to move the contacts 114

and 118 into engagement. This energizes the retracting solenoid 20 through the conductors 115, the generator 105, the conductor 127, the slip ring 126, the current then passing 5 through the conductors 64 of the wire cable and through the groups of the retracting unit 20 and returning through the slip ring 122 and conductor 121.

The energization of the retracting solenoid 10 draws the plunger up until the retracting armature 78 bridges the magnetic path of the retracting unit 20 and lies in such a position that it contacts the sleeve 37.

During the time that the cam 96 allows the 15 contacts 91 and 93 to close, the cam 94 turns into such a position that the contact 90 engages the contact 92, thus completing a circuit through the solenoid 100 through the conductors 102, 104, and 106. This energizes 20 the solenoid 100 to close the contacts 113 and 117 which in turn completes a circuit through the conductor 120, the slip rings 122 and 126, and the conductors 127 in a manner to energize the advancing solenoid. This does not 25 materially move the plunger downward, however, due to the contact magnetic action between the sleeve 37 and the retracting armature 78 but exerts a strong downward force on this plunger.

30 When the flux through the advancing solenoid has built up to a maximum, the cam 95 operates to separate the contacts 93 and 95 thus de-energizing the solenoid 101 and allowing the spring 112 to separate the contacts 114 and 118. The switch 134 having 35 been previously closed, the arc which is formed between these latter contacts is quickly blown out by the magnetic blow-out means which places these separating contacts in a 40 strong magnetic field. The current through the retracting solenoid is thus quickly reduced to zero, and inasmuch as the retracting force is thus removed from the armature 78 the plunger moves swiftly downward under 45 the influence of the advancing solenoid. Due to the fact that the flux of this advancing solenoid has previously built up to a maximum, this downward movement of the plunger is fast, and the blow struck by the bit 19 50 is a very hard one, especially if the instant of impact occurs just prior to the instant that the maximum downward thrust is exerted on the plunger.

Subsequently the cam 94 moves into such 55 a position as to separate the contacts 90 and 92, thus breaking the circuit through the advancing solenoid upon separation of the contacts 113 and 117, after which the cycle is repeated.

60 If the plunger moves downward a sufficient distance for the roller 200 to enter the annular channel 204, the signal lamp 215 will light. If the lowering of the drilling unit is being manually controlled, this is a signal 65 that the drum 15 can be turned slightly to

allow a slight lowering of the drilling structure. After this lowering it may be several strokes of the plunger before the bit has penetrated sufficient to allow the roller to again engage the annular channel. In this way the 70 operator attempts at all times to keep the signal lamp flashing and yet advance the drilling structure at such a rate that the time interval between flashes immediately after each lowering will not be excessive. 75

Should the drilling structure be lowered too fast, or should the bit encounter an excessively hard strata, this signal lamp will fail to light and the operator will draw upward on the cable until such time as the signal lamp again lights with each reciprocation, after which he will relower the drilling structure more slowly. 80

In the event that automatic operation is desirable, the time-limit relay is connected 85 across the terminals of the signal lamp so that each time an electric impulse passes through the control circuit the cable will be lowered by an amount determined by the setting of the time-limit relay. I prefer to so 90 set this relay that the amount of advancement is each time somewhat greater than the distance penetrated by the bit on each stroke, thus allowing several strokes to be completed 95 between advancements. This is not, however, necessary where the number of strokes per minute is low. 100

While I have described the drilling structure as comprising a single retracting solenoid and a single advancing solenoid, it 105 should be clear that this has been done only for the purpose of clearness and simplicity. In actual drilling it is often necessary to use as many as ten retracting and ten advancing units, though it is not necessary that the number of retracting and advancing units be equal. For these additional units I prefer to use a solenoid unit such as that described 110 in detail for the retracting unit 20, the additional retracting units and the corresponding spacing structures being inserted at a section A—A of Fig. 2, these units being inserted with the primary sleeve 37 of each unit upward so that the contact magnetic action 115 when the plunger is retracted will be obtained. Similarly the units to be used as retracting units are inserted, together with a corresponding number of spacing structures, at a section B—B and are secured in place 120 with the primary sleeves 37 of each downward, thus increasing the thrust in a downward direction just prior to the instant that the advancing armatures contact therewith. 125

It is not, however, necessary in all cases to use one sleeve of magnetic material and the other of non-magnetic material for very desirable results can also be obtained by making both of non-magnetic material so that no magnetic binding takes place at any portion 130 of the stroke. 135

While I have shown and described a preferred embodiment of my invention and a preferred method of operation therefor, it should be clear that various modifications 5 might be made therein without departing from the spirit of this invention. Thus, changes in form and proportion of many of the elements might be made to fit circumstances under which the drilling structure is 10 to be operated, and the particular method of threading the plugs and retaining members in place may be dispensed with in favor of other methods. Certain features of my invention are furthermore not limited to a 15 drilling structure of the type shown but may be used on other reciprocating mechanisms.

The particular cycle of operations is an important part of this invention, as is also the provision of means for circulating the 20 water in the well in cooling relationship with the solenoid windings, for by the latter means I am able to operate the drilling structure with the magnetic paths of the solenoids substantially saturated without danger of over- 25 heating. Asbestos impregnated windings may be resorted to in certain installations wherein the water is not cold or wherein drilling is especially difficult, thus greatly increasing the life of the solenoid units under 30 heated conditions. The particular unit type of construction is also an important part of my invention, as is also the indicating means at the top of the ground and the automatic advancing means. Various methods of ac- 35 complishing this automatic advancement will be apparent to those skilled in the art, the two systems shown in Figs. 9 and 10 being illustrative only.

I claim as my invention:

40 1. In a drilling structure, the combination of: a plunger; a primary solenoid means for moving said plunger in a given direction; a secondary solenoid means acting on said plunger in a direction opposite to that of said 45 primary solenoid means; supply means for energizing said primary and secondary solenoid means; control means for de-energizing said primary solenoid means during the period of energization of said secondary solenoid means; and means for quickly decreasing the current in said primary solenoid means when said primary solenoid means is de-energized.

50 2. In a drilling structure, the combination of: a plunger having upper and lower sections of magnetic material separated by a section of non-magnetic material; upper solenoid means around said plunger and adapted to act on said upper section of magnetic material; lower solenoid means around said plunger and adapted to act on said lower section of magnetic material, said upper and lower solenoid means being spaced center-to-center a distance unequal to the center-to- 55 center spacing of said sections of magnetic

material; and upper and lower closure means at each end of each of said solenoid means, the upper and lower closure of each solenoid means being spaced a distance apart substantially equal to the length of its corresponding section of magnetic material whereby said sections of magnetic material bridge the closure means of said upper and lower solenoid means when said plunger is in an upper and a lower position respectively. 75

3. In a drilling structure, the combination of: a plurality of substantially identical solenoid units; a plurality of substantially identical spacing structures, one of said spacing structures being positioned between each pair of said solenoid units; individual means for securing each spacing unit to the solenoid units on opposite ends thereof whereby any solenoid unit may be replaced without disturbing the remainder of the solenoid units; 80 and a plunger slideable relative to said solenoid units and said spacing structures, said plunger being formed of alternate magnetic and non-magnetic sections. 85

4. A combination as defined in claim 3 including conductors for connecting said solenoid units together and in which each of said solenoid units provides pull-box means into which any excess lengths of said conductors may be forced when assembling said drilling structure. 90

5. A combination as defined in claim 3 in which said spacing structures provide passages formed therethrough and which communicate with passages formed in said solenoid units when properly secured thereto. 100

6. In a solenoid unit of the class described, the combination of: a shell; a central plunger-receiving tubing extending through said shell; means at opposite ends of said shell and extending between said shell and said central tubing for defining an annular space therebetween; a packing means sealing each end of said annular space; and a winding in said annular space. 105

7. In a drilling means, the combination of: a drilling structure positioned in a well and comprising solenoid means energized from the top of said well; plunger means adapted to be both raised and lowered by said solenoid means; drilling means actuated by said plunger means; lowering means at the top of said well for controlling the position of said drilling structure in said well; and means operated as a function of the degree of advancement of said plunger means relative to said solenoid means for controlling the movement of said lowering means. 110

8. In a drilling means, the combination of: a drilling structure positioned in a well and comprising solenoid means energized from the top of said well; plunger means adapted to be both raised and lowered by said solenoid means; drilling means actuated by said plunger means; lowering means at the top of 115

said well for controlling the position of said drilling structure in said well; a switch in said drilling structure; means for operating said switch when said plunger has reached a 5 position just prior to the position of maximum thrust; and control means for controlling said lowering means and operatively connected to said switch.

9. In a drilling means, the combination of: 10 a drilling structure positioned in a well and comprising solenoid means energized from the top of said well; plunger means adapted to be both raised and lowered by said solenoid means; drilling means actuated by said 15 plunger means; lowering means at the top of said well for controlling the position of said drilling structure in said well; a switch in said drilling structure; means for operating said switch when said plunger has reached a 20 position just prior to the position of maximum thrust; and a time-limit relay electrically connected to said switch for controlling said lowering means.

10. A method of applying slow building- 25 up forces in effective quick motion of an element, which includes the steps of: building up of one of said forces to move said element into a retracted position; building up a second force acting on said element in opposition to the first force; and suddenly removing said first force during the application of said second force to allow said second force to quickly advance said element.

11. In a drilling structure adapted to be 30 lowered into a well containing a liquid, the combination of: solenoid means; a hollow plunger adapted to be reciprocated by said solenoid means; and a pumping means associated with said plunger and operated by a 40 reciprocation thereof for circulating said liquid through said plunger.

12. In a drilling structure adapted to be lowered into a well containing a liquid, the combination of: solenoid means; a hollow 45 plunger adapted to be reciprocated by said solenoid means; walls defining a cylinder in said drilling structure into which said plunger extends, said cylinder communicating with the interior of said plunger through a valved 50 passageway; valved inlet means for conducting said liquid into said cylinder; and a piston on said plunger for drawing said liquid into said cylinder and circulating it through said plunger in cooling relationship 55 with said solenoids.

13. In combination: a shell; a central tubing extending through said shell; primary and secondary closure means extending between said shell and said central tubing to 60 define an annular space; a winding in said annular space but smaller than said annular space to provide a wiring space between itself and one wall of said annular space; walls defining a passage through each of said primary and secondary means; means positioned

at opposite ends of said shell for preventing communication between the interior of said central tubing and said passages of said means, and providing passages communicating with said first named passages; and conductors carrying electric current to said winding and extending through all of said passages.

14. In combination: a shell; a central tubing extending into said shell and cooperating therewith in defining an annular space; closure means extending between one end of said shell and said central tubing, said central tubing engaging said closure means; closure means at the other end of said shell and movable therein toward said first named closure means to compress said central tubing between said closure means; and a winding in said annular space.

15. In combination: a solenoid unit comprising a shell, a central tubing spaced to form an annular space therebetween, and a winding in said annular space; a spacing structure adapted to be secured to the end of said solenoid unit and providing a passage; 85 conductor means positioned in said passage and electrically connected to said winding; and walls defining a pull box adjacent that end of said solenoid unit to which said spacing structure is secured and into which any 90 excess conductor means may be forced when said solenoid unit and said spacing structure are being assembled.

16. In combination: a shell formed of magnetic material; a winding in said shell; 100 a plunger movable through said winding; a primary annular closure means extending across one end of said shell and providing an opening only slightly larger in diameter than said plunger, said primary closure means being formed of magnetic material; and a secondary closure means providing an 105 opening only slightly larger in diameter than said plunger and bounded by walls formed of a non-magnetic material, said plunger being formed of magnetic material and being of sufficient length to bridge said primary and secondary closure means, whereby an extremely strong pull is exerted on said plunger when one end thereof is approaching said primary closure means.

17. A combination as defined in claim 16 including a percussion tool attached to that end of said plunger closest to said primary closure means.

18. In a drilling structure, the combination of: a plunger having upper and lower sections of magnetic material separated by a section of non-magnetic material, upper solenoid means around said plunger and adapted to act on said upper section of magnetic material; lower solenoid means around said plunger and adapted to act on said lower section of magnetic material; means formed of magnetic material associated 120

with one of said solenoid means and contacting said plunger to exert a contact magnetic action on one section of said plunger when said plunger is in an upper position; 5 and means formed of magnetic material associated with the other of said solenoid means and contacting said plunger to exert a contact magnetic action on the other section of said plunger when said plunger is in 10 a lower position.

19. In combination: a shell formed of magnetic material; a primary and a secondary closure means extending inward from opposite ends of said shell and providing openings; a plunger only slightly smaller in diameter than said openings so as to be slidably journaled therein; a central tubing formed of non-magnetic material and extending between said closure means, said central tubing 15 providing an inner wall of greater diameter than said opening so as to be spaced from the surface of said plunger, said shell and said closure means cooperating with said central tubing in providing an annular space; and a 20 winding in said annular space and capable when energized of exerting a pull on said plunger.

20. In combination: a plunger; a primary solenoid means acting when energized to 30 retract said plunger; a secondary solenoid means acting when energized to advance said plunger; primary switch means for energizing said primary solenoid means to retract said plunger; secondary switch means for 35 energizing said secondary solenoid means; means for closing said secondary switch means during the energization of said primary solenoid means whereby both of said solenoid means act on said plunger in opposite directions; and means for opening said primary switch means to de-energize said primary solenoid means during the period of energization of said secondary solenoid 40 means to advance said piston under the action of the force exerted by said secondary solenoid means.

21. In combination: a plunger; a primary solenoid means acting when energized to 50 retract said plunger; a secondary solenoid means acting when energized to advance said plunger; and means for energizing said solenoid means in a cycle comprising energization of said primary solenoid means to retract said plunger, subsequent energization of said secondary solenoid means during the period of 55 energization of said primary solenoid means, de-energization of said primary solenoid means during the energization of said secondary solenoid means thereby to advance said plunger, and subsequent de-energization of 60 said secondary solenoid means to complete said cycle before the re-energization of said primary solenoid means on a succeeding cycle.

22. In a drilling structure adapted to be 65 lowered into a well, the combination of: a

plurality of annular solenoids; a plunger extending through said solenoids and reciprocated thereby, said plunger providing a central bore therethrough; walls at one end of said plurality of solenoids and defining a cylinder into which one end of said plunger extends; discharge valve means through which said central bore communicates with said cylinder; and a relatively large intake valve means communicating between said cylinder 70 and a body of cooling liquid whereby on the retracting movement of said plunger cooling liquid is forced through said central bore in cooling relationship with said solenoids and on the advancing movement of said plunger a new supply of said cooling liquid moves into 75 said cylinder through said relatively large intake means and effecting a minimum of retarding action on said plunger.

In testimony whereof, I have hereunto set 80 my hand at Los Angeles, California, this 14th day of August, 1929.

JOHN L. SAGER.

CERTIFICATE OF CORRECTION.

Patent No. 1,891,062.

December 13, 1932.

JOHN L. SAGER.

It is hereby certified that error appears in the printed specification of the above numbered patent requiring correction as follows: Page 8, line 25, claim 10, for "effective" read "effecting"; and that the said Letters Patent should be read with this correction therein that the same may conform to the record of the case in the Patent Office.

Signed and sealed this 7th day of February, A. D. 1933.

M. J. Moore,

Acting Commissioner of Patents.
